UNITED STATES PATENT OFFICE.

LOUIS A. KRAMER, OF CHICAGO, ILLINOIS.

CARCASS-DEHAIRING MACHINE.

Application filed June 1, 1925. Serial No. 34,272.

My invention relates to machines for dehauling, cleaning and massaging carcasses; namely, the general class of machines commonly employed for cleaning freshly killed 5 hogs after they have been taken out of the scalding tank. In some of its general objects, my invention aims to provide a dehauling machine of this general class which will have a high operating capacity in proportion to its size, which will be equally well adapted for thoroughly cleaning and dehauling carcasses of widely varying sizes, which will avoid an entangling of the legs or other parts of the hog with any part of 10 the machine in a manner adapted to produce a cutting of the skin, and which will require comparatively few and easily replaced parts in proportion to its operative capacity. It also provides a novel method 15 for advancing carcasses successively past a plurality of dehauling mechanisms. Furthermore, my present invention provides a machine for this purpose in which the carcass is continuously supported by rotating 20 members during the dehauling operation and in which the disposition of these members cooperates with the distribution of weight in the carcass for automatically feeding the carcass through the machine without 25 requiring any auxiliary mechanism.

More particularly, my invention provides a machine of this class in which the carcass is supported entirely by rotating members while passing through the field of the dehauling operation, in which these rotating members all tend to rotate the hog in the same direction about its longitudinal axis; in which the rotating members include collars disposed for peripherally engaging the 30 carcass, and also include beating and scraping elements disposed for engaging the carcass and for moving along the surfaces of the carcass at a higher rate of speed than the carcass-engaging peripheral portions of 35 the said collars, and in which the collars and the beating and scraping elements are relatively so disposed as to prevent the legs of the carcass from being entangled in or cut by any part of the machine.

My invention also aims to provide a machine of this class in which certain of the scraper elements are disposed for engaging the carcass with an effectiveness dependent 40 on the weight of the engaged carcass portion, in which this difference in effectiveness will automatically cause the longitudinal

axis of the hog to be disposed at an angle to the axis about which the beating elements revolve, and in which the resulting angular disposition will thereafter cause these scraping elements to exert an obliquely forward pulling effect on the carcass so as to cause the carcass to move a substantially spiral motion through the machine. 45

My invention also provides a conveyor for feeding the carcasses endwise into the machine in such a manner that the head end of the carcass will be engaged by dehauling elements before the tail end leaves the conveyor, thereby facilitating the said angular disposition of the carcass. 50

My invention also provides a machine of this general type in which such an automatic feeding of the carcass through the machine can be produced while employing rotating elements all secured to horizontal and parallel axes, in which an exceedingly simple driving mechanism can be employed for rotating the parallel shafts by which the said elements are carried, and in which the carcass cannot wedge between any of the parts of the machine which support it. Furthermore, my invention provides a machine which can readily be constructed with varying arrangements of the rotating parts and 55 with the number of beating and scraping elements increased according to the desired extent of the scraping, beating and massaging effect. Still further and also more detailed objects will appear from the following 60 specification and from the accompanying drawings, in which

Fig. 1 is a vertical transverse section through a machine embodying my invention.

Fig. 2 is a horizontal section taken along 65 the line 2-2 of Fig. 1.

Fig. 3 is a fragmentary vertical section through the same machine taken longitudinally of the machine along the line 3-3 of Fig. 2. 70

Fig. 4 is a view taken from the left hand of Fig. 2 to show the driving connections between the shafts of the machine.

Fig. 5 is a vertical transverse section similar to Fig. 1, but showing another arrangement of the rotating members, namely one employing a medial lower shaft carrying collars only and also employing a medial upper shaft disposed above the carcass. 75

Fig. 6 is a fragmentary longitudinal section through the machine along the line 6-6 of Fig. 7. 80

Fig. 7 is a horizontal section through the same machine taken along the line 7-7 of Fig. 5.

Fig. 8 is a view taken from the left hand of Fig. 7 (or the discharge end of the machine) showing the driving connections between the shafts which extend horizontally and longitudinally of the machine.

Figs. 9 to 13 are diagrammatic views showing five other arrangements of the beater and collar mechanisms of my machine.

Fig. 14 is a bottom view of the portions of the machine shown in Fig. 11.

Fig. 15 is a bottom view of the portions of the machine shown in Fig. 12.

Fig. 16 is a bottom view of a hog passing through the machine, showing a few of the scraping elements as they appear when initially engaging the hog, the inclination of the hog to the axis of the rotating shafts being exaggerated in this view.

Fig. 17 is a bottom view similar to Fig. 16, showing the position of the same parts when the same scrapers are releasing their grip on the hog.

Fig. 18 is an end view of the same hog, showing the positions of a roller on the adjacent shaft and of the scrapers which have a lateral and upward pulling movement on the hog.

Fig. 19 is an end elevation of one of the collars on the shaft 3 of Fig. 1, showing the fluting of the periphery of this collar.

In the embodiment of Figs. 1 to 4 inclusive, my machine includes five parallel shafts which carry the elements employed for rotating and dehauling the hog and for feeding it through the field of the dehauling operation. These shafts, numbered from 1 to 5 inclusive, have their axes disposed as longitudinal elements of a trough-like surface and each of these shafts has fastened to it a plurality of collars 11, which collars are spaced along the shaft and here shown as of uniform diameter. The collars on the several shafts are desirably in alignment transversely of the shafts and are of such a diameter that the peripheries of the collars on adjacent shafts are relatively close to each other, thereby permitting the hog to bear simultaneously against the collars on any two adjacent shafts without having its weight press a flabby portion of the hog materially into the space between these collars.

Fastened also to each of the shafts 1 to 5 inclusive are beater members, each of which consists of a collar 12 fastened to the inner ends of a plurality of flexible beaters 13, each beater carrying a bent claw or scraper 14 at its free end. The length of the flexible beater portions 13 is such that these normally extend beyond the collars 11 carried by the same shaft, and also de-

sirably such that the scrapers 14 will reach between the collars on an adjacent shaft. To afford this reach while maintaining a relatively close spacing of the shafts, I desirably stagger the beaters on adjacent shafts longitudinally of the machine, so that each of the said beater members is opposite a portion on the next shaft which does not have beater members there, this being shown in Figs. 1 to 3 inclusive.

All of the shafts 1 to 5 are continuously rotated in one direction during the operation of the machine, for which purpose I am showing an elevated drive shaft 6 driven from a pulley 10 and carrying a sprocket 7 which is operatively connected by a chain 8 to sprockets 15 fastened respectively to the shafts 1 to 5 inclusive, an adequate engagement of the chain with the driven sprockets 15 being secured by idler sprockets 9 interposed between the consecutive sprockets 15 as shown in Fig. 4.

I also provide suitable means for feeding hogs endwise into the machine from one end of the heretofore described operating mechanism so as to project the hog into the trough-like arrangement of rotating members carried by the shafts 1 to 5 inclusive. For this purpose I am showing the shaft 5 as carrying a worm 16 meshing with a worm wheel 17 on a shaft 18 which extends transversely of the machine, which transverse shaft actuates a belt conveyor 19 provided with riser strips 20 for engaging the hog while conveying the latter to the dehauling mechanism. This conveyor desirably slopes upwardly towards the machine and has its discharge end disposed considerably above the lower collars 11 of the machine, so that the hog will dip downward into engagement with parts of the dehauling mechanism when it is being fed into the machine.

The spread of the said trough-like arrangement of the rotating members carried by the shafts 1 to 5 inclusive is effectively greater than the diameter of the largest hog which is to be dehaired, thereby permitting the longitudinal axis of even a large hog to be swung at an angle to the axes of the parallel shafts 1 to 5. When the hog is disposed within the said trough-like arrangement of mechanism, as shown in dotted lines at 21 in Fig. 1, the collars 11 on the three lower shafts 2, 3 and 4 are disposed for supporting the hog. Since these shafts all rotate in a direction which is clockwise in Fig. 1, the collars combine in rotating the hog in a counterclockwise direction, the rotating effect being substantially uniform in speed for these collars, and this effect is positive owing to the pressure exerted by the weight of the hog.

The flexible beaters 13 and the scrapers 14 on the shafts 1 to 5 will likewise tend to

rotate the hog in the same direction, but the portions of these beater members which engage the hog are at much greater distance from the axes of the corresponding shafts than the uniform radius of the collars, hence these beaters and scrapers will drag somewhat along the surface portions of the hog with a scraping and dehairing action. The beater members on the shafts 1 and 2 will also tend to force the hog toward the right in Fig. 1 and hence will tend to roll it upwards on the collars carried by the shaft 3. The scrapers on the beater mechanism carried by the shaft 4 will likewise tend to raise the hog and to pull it up on the collars carried by the same shaft. Consequently, the hog, while continuously rotated in one and the same direction, will intermittently rise out of contact with the collars on the lower shaft and then drop back somewhat by gravity, thereby shifting its position and making the beater mechanisms more effective in reaching all portions of the hog.

However, the said pulling and lifting action of the scrapers carried by the shaft 4 will not be the same at longitudinally spaced portions of the hog, owing to the uneven distribution of weight in this animal, the forward end being considerably heavier than the rear end. Since each of the scrapers carried by the shaft 4 initially engages the hog substantially at the lowest point of the latter which is opposite that scraper transversely of the machine, the force with which the weight of the hog presses against the scraper and causes a flexing of the beater 13 to which that scraper is fastened will vary with the weight of the engaged portion of the hog. Consequently, there is a less effective pulling on the rear portions of the hog than on the more forward portions, it being easier for the less effectively pressed scrapers opposite the rear portion of the hog to slip on the surface of the latter. For this reason, the forward end of the hog will be drawn upward and towards the right in Fig. 1, while gravity will permit the rear end of the hog to remain more approximately opposite the middle of the trough-like mechanism, thereby causing the longitudinal axis 22 of the hog to be disposed at an acute angle to any line parallel to the axis of the aforesaid shafts, such as the line 23 in Fig. 16.

With the hog thus disposed, each scraper 14 first engages the hog adjacent to its then lowermost portion, as shown in Figs. 16 and 18 (Fig. 16 being a bottom view) and then exerts an action which tends to pull the hog up on the adjacent rollers 11 carried by the same shaft and which also tends to lift the hog. In thus moving from the position of the beater 13 in Fig. 18 to that shown in dotted lines for the same beater after

the shaft 4 has rotated sufficiently to allow the scraper on that beater to slip off the hog, the pulling action is not at right angles to the axis of the hog (or along the line 24 of Fig. 16) but is oblique to that axis as shown in the line 25. Consequently, this combined pulling and rotating action of the scraper also draws the hog forward to a corresponding extent, thereby advancing it for the distance marked 26 in Fig. 17. By the time the previously active scraper 14 releases its grip on the hog, the next scraper carried by the same beater collar 12 grips the then lowest portion of the hog opposite it and continues the advancing action. Hence the hog is automatically fed head foremost through the machine by the dehairing mechanism itself with a spirally advancing movement, without requiring conveyors, inclined bars, push arms or other mechanism for feeding it through the field of the dehairing operation. Moreover, by feeding the hog head foremost into the machine and disposing the discharge end of the conveyor somewhat above the lower hog-rotating collars in the machine, I cause this tilt-effecting and advancing action on the hog to begin as soon as the forward portion of the hog is engaged by the beater members near the receiving end of the machine.

By thus having the hog supported entirely by rotating members while it is passing through the field of the dehairing operation, I avoid any dragging action such as is frequently encountered in machines using stationary supporting elements, and I also make it easy for the beater members to exert their above described advancing or feeding effect on the hog. In practice, I desirably employ a large number of collars on each shaft with a relatively close spacing between them, so that the hog will continuously be supported by a considerable number of these collars. I also desirably place collars so close to the flexible beater elements as to prevent the legs of the hog from being caught between these flexible beater strips and the collars. The collars themselves may have all smooth peripheries, or some of them may have their peripheral portions longitudinally fluted (after the manner shown for example in Fig. 19 and on the collars mounted on a shaft 3 in Figs. 1 and 2) so as to increase their rotating and massaging effect on the hog.

Moreover, the number of shafts and the number and arrangement of the elements carried by them may be varied considerably, as also the relative positions of the beater-carrying shafts with respect to the path traversed by the hog while being dehaired. For example, Fig. 5 shows a machine arranged substantially similar to that of Fig.

1, but having no beater members either on the lateral shafts 1 and 5 or on the lowermost shaft 3. It also shows the drive shaft 6 as carrying beater members each including a flexible beater strip 27 carrying a series of scrapers 28 spaced longitudinally along that strip.

Fig. 10 shows an arrangement employing only four rotating mechanisms and having beater members only on two shafts alternating with the other two shafts.

Fig. 12 also shows a four shaft arrangement, but one in which beater members are employed only on the two lateral shafts.

Fig. 9 shows an eight shaft arrangement in which the axis of the shafts are disposed in a circle and in which beater members are provided only on the uppermost and lowermost shafts and on the two extreme lateral shafts.

Fig. 11 shows a three shaft arrangement in which beater members are only employed on the lower shaft; while Fig. 13 shows a three shaft arrangement in which beater members are employed on the two lateral and elevated shafts.

In each case, it will be evident that the hog will be supported entirely by rotatable members and that the disposition of the beater members on one or more shafts will have the above described actions which results in feeding the hog automatically through the machine, thus embodying the same novel method. With the arrangements employing beater members on only one or two shafts, the cost of the machine will be considerably lower than it will if constructed with beater members on a larger number of shafts. Hence my machine can readily be built to suit packing plants of different daily operating capacities. So also, since my presented construction permits the simultaneous and effective engagements of the hog by a large number of beating and scraping elements, I can secure an unusually large capacity in proportion to the floor space, weight and cost of the machine.

However, while I have particularly described some typical arrangements and have illustrated some desirable structural features, I do not wish to be limited to the details of the construction and arrangement thus disclosed. Obviously, many changes might be made in the same without departing either from the spirit of my invention or from the appended claims. For example, Figs. 5, 11 and 13 show beater mechanisms in which spider arms 29 are substituted for the beater-carrying collars 12 of the mechanisms shown in Figs. 1, 9 or 12.

I claim as my invention:—

1. In a machine for dehairing a hog, a plurality of groups of collars having the

axes of the several groups parallel and horizontal and disposed in trough-like formation, the collars of each group being spaced along the axis of that group and all of the collars rotating in the same direction, and rotating scraper mechanisms coaxial with and between certain of the collars and reaching radially beyond the latter, the collars forming the sole support for the hog while in the field of the scraper mechanisms.

2. In a hog dehairing machine, a plurality of parallel and rotating shafts having their axes disposed in substantially a trough-shaped formation, and beaters fast with respect to each shaft and spaced along the same, the shafts being disposed so that the beaters cooperate in forcing the hog toward one side of the trough-shaped formation, the beaters on a shaft adjacent to that side being disposed so as to engage the hog initially at its bottom and to draw it toward that side with a rotating and lifting action, in combination with auxiliary rotating and supporting mechanism having portions disposed for engaging the hog simultaneously with some of the beaters and tending to rotate the hog in the same direction that it is rotated by the beaters but at a higher speed of rotation, the said portions including rotating discs spaced longitudinally of the trough shaped formation.

3. In a hog dehairing machine, a plurality of parallel and rotating shafts having their axes disposed in substantially a trough-shaped formation, and beaters fast with respect to each shaft and spaced along the same, the shafts being disposed so that the beaters cooperate in forcing the hog toward one side of the trough-shaped formation, the beaters on a shaft adjacent to that side being disposed so as to engage the hog initially at its bottom and to draw it toward that side with a rotating and lifting action, in combination with auxiliary rotating mechanism having portions disposed for engaging and supporting the hog simultaneously with some of the beaters and tending to rotate the hog in the same direction that it is rotated by the beaters but at a higher speed of rotation, the said portions including rotating discs spaced longitudinally of the trough shaped formation and respectively disposed between certain of the beaters for rotating and supporting the hog during the dehairing operation.

4. A machine for dehairing a hog fed lengthwise into the machine from one end thereof, comprising a plurality of rotatable members having parallel and substantially horizontal axes extending longitudinally of the machine with the said axes arranged in a trough shaped formation, certain of the said members having dehairing elements

adapted to engage the hog and all being disposed for rotating the hog so that its lowermost portion moves towards the same side of the machine, the said rotatable members forming the entire support for the hog during its dehairing and the sole means for feeding the hog endwise and longitudinally of the said axes, the spread of the shafts being such as to permit the hog to be disposed oblique to the said axes so as to cause the dehairing elements to effect such feeding.

5. A machine for dehairing a hog fed lengthwise into the machine from one end thereof, comprising rotatable members spaced along a plurality of parallel and substantially horizontal axes extending longitudinally of the machine with the said axes arranged in a trough shaped formation, certain of the said members having dehairing elements adapted to engage the hog and all being disposed for rotating the hog so that its lowermost portion moves towards one side of the machine, the said rotatable members forming the entire support for the hog during its dehairing and the sole means for feeding the hog lengthwise through the machine, the spread of the shafts being such as to permit the hog to be disposed oblique to the said axes while passing through the machine.

6. A machine for dehairing a hog fed lengthwise into the machine from one end thereof, comprising rotatable members spaced along a plurality of parallel and substantially horizontal axes extending longitudinally of the machine and of the hog, certain of the said members having dehairing elements adapted to engage the hog and dispose for drawing the front and rear of the hog toward one side of the machine to an extent varying with the relative weight of the front and rear hog portions so as to dispose and maintain the axis of the hog oblique to the aforesaid axes, the said rotatable members forming the entire support for the hog during its dehairing and the sole means for feeding the hog lengthwise through the machine, and the said rotatable members being disposed for holding the hog out of contact with stationary parts of the machine throughout the dehairing operation.

7. A machine for dehairing a hog fed lengthwise into and through the machine from one end of the machine, comprising a plurality of rotatable members having parallel and substantially horizontal axes extending longitudinally of the machine with the said axes disposed substantially in a trough-shaped formation, certain of the said members having dehairing elements adapted to engage the hog and all being disposed for rotating the hog so that its lowermost portion moves towards one side

of the machine, the said rotatable members forming the entire support for the hog during its dehairing and its advancing through the machine, the dehairing elements on one of the rotatable members being yieldingly mounted and disposed for drawing the hog toward the said side with a lifting action varying in effect with the weight of the hog portion engaged by the said elements, whereby the distribution of weight in the hog causes its forward portion of the hog to be drawn further toward the said side than its rearward portion so that the said elements will move obliquely forward with respect to the hog while in engagement with the hog, thereby feeding the hog lengthwise through the machine.

8. In a hog dehairing machine, a plurality of parallel and substantially horizontal shafts continuously rotating in the same direction, and a plurality of collars and rotary scraper mechanisms fastened to and spaced along the shafts and cooperating to afford the entire support for a hog while the hog is passing endwise through the machine.

9. In a hog dehairing machine, a plurality of rotating dehairing mechanisms having a common axis and spaced along that axis, and rotating collars disposed respectively between consecutive dehairing mechanisms and cooperating with the latter in supporting the hog while the latter is moved endwise longitudinally of the said axis by the action of the dehairing mechanisms.

10. In a hog dehairing machine, a horizontal shaft, a plurality of dehairing members fast on the shaft, a plurality of collars also fast on the shaft and respectively between consecutive dehairing members, a second horizontal shaft parallel to the first named shaft, collars on the second shaft in transverse alignment with the dehairing members on the first shaft, and means for rotating both shafts in the same direction.

11. In a hog dehairing machine, a plurality of parallel shafts all rotating in the same direction, one of the shafts being disposed between and lower than two other shafts, hog-rotating collars fast on all of the said shafts and spaced longitudinally along each shaft, and flexible beater members fastened to and spaced along at least one of the shafts, and reaching out radially of the shaft carrying the same beyond the collars fastened to the same shaft or shafts.

12. In a hog dehairing machine, a plurality of parallel shafts all rotating in the same direction, one of the shafts being disposed between and lower than two other shafts, hog-rotating collars fast on all of the said shafts and spaced longitudinally along each shaft, and flexible beater members fastened to and spaced along at least one of the shafts, and reaching out radially of the

6
shaft carrying the same between collars fastened to an adjacent shaft.

13. A hog dehairing machine as per claim 10, in which the beater members on one shaft move upwardly and laterally outwardly of the machine while engaging the hog, and in which the collars rotate so as to move the hog toward the said shaft.

14. A hog dehairing machine as per claim 10, in which the collars on adjacent shafts are in alignment transversely of the shafts and in which the transversely aligned collars have their peripheries close to each other.

15. A hog dehairing machine as per claim 10, in which two adjacent shafts have flexible beater members fastened thereto, the beater members on the two shafts being staggered longitudinally of the machine.

16. In a hog dehairing machine, a plurality of parallel and substantially horizontal shafts continuously rotating in the same direction, and a plurality of collars and rotary scraper mechanisms fastened to and spaced along the shafts and cooperating to afford the entire support for a hog while the hog is passing endwise through the machine, and a conveyer arranged for feeding the hog endwise into the machine from one end thereof.

17. A hog dehairing machine as per claim 15, in which two adjacent shafts have flexible beater members fastened thereto, the beater members on the two shafts being staggered longitudinally of the machine, the discharge end of the conveyer being higher than the collars upon which the hog rests while in the field of the dehairing operation.

18. Hog dehairing mechanism including a pair of parallel shafts, and a series of beater members fast upon and spaced along each shaft, and collars fast on each shaft and alternating with the beater members, each beater member being transversely opposite a collar on the other shaft.

19. Hog dehairing mechanism including a plurality of parallel shafts, beater members fast upon and spaced along one shaft and collars fast upon a shaft adjacent to the aforesaid shaft, the said collars being disposed so that each beater moves between a pair of the collars, the spacing between the axes of the said two shafts being less than the sum of the radius of each collar and the radial reach of each beater member.

Signed at Chicago, Illinois, May 29th, 1925.

LOUIS A. KRAMER.
